UNITED STATES PATENT OFFICE.

FRANK RHIND, OF MERIDEN, CONNECTICUT.

DESIGN FOR A GAS-BURNER.

SPECIFICATION forming part of Design No. 18,535, dated August 14, 1888.
Application filed June 11, 1888. Serial No. 276,779. Term of patent 14 years.

To all whom it may concern:

Be it known that I, FRANK RHIND, residing at the city of Meriden, county of New Haven, State of Connecticut, and a citizen of the United States, have invented and produced a new and original Design for Gas or other Illuminating Burners of the Argand Type, of which the following is a specification, reference being had to the accompanying drawing, forming part hereof.

The drawing is an elevation or side view of my newly-designed burner, a single view being deemed sufficient to fully illustrate the same.

The leading features of my design consist in 15 a perforated cone, which surrounds the burner-tip, and a central perforated tube or cone within the burner-tip, surmounted by a basket-shaped chamber, the top of which is closed and the lower side walls preferably perforated and 20 contracted so as to fit the top of the central tube or cone.

Referring to the drawing, A represents the outer perforated cone which surrounds the burner-tip.

B is the central perforated tube or cone 25 within cone A and the burner-tip, extending a certain determined distance above cone A; and C, the basket-shaped chamber, the side walls of which are perforated and contracted at the bottom, so as to fit the top of the perforated tube or cone B, to which it is attached. A base bead or flange, D, which is expanded and formed into a beveled bottom rim, D', is attached to the bottom of cone A.

Having fully described my newly-designed 35 burner, I claim and desire to secure by Letters Patent of the United States—

In the design for gas or other illuminating burners herein shown and described, the outer perforated cone, A, the central perforated tube or cone, B, and the basket-shaped 40 chamber C on the top of the tube or cone B, the side walls of which are perforated, as set forth.
